UNITED STATES PATENT OFFICE.

WILLIAM H. HEILIGER, OF BRAZIL, INDIANA.

WHIP-LOCK.

No. 899,695.

Specification of Letters Patent.

Patented Sept. 29, 1908.

Application filed March 27, 1908. Serial No. 423,726.

To all whom it may concern:

Be it known that I, WILLIAM H. HEILIGER, a citizen of the United States, residing at Brazil, in the county of Clay, State of Indiana, have invented certain new and useful Improvements in Whip-Locks; and I do hereby declare the following to be a full, clear, and exact description of the invention, such as will enable others skilled in the art to 10 which it appertains to make and use the same.

This invention relates to certain new and useful improvements in whip locks.

The object of my invention is, to provide a 15 whip socket arranged to be attached to the dash board of a wagon or carriage, so that when desired the whip may be securely locked within the socket, the whip however, being so held that the same may be 20 instantly released by means of a key, as will be described more fully hereinafter.

In the accompanying drawings Figure 1 shows an elevation of a whip lock constructed according to my invention. Fig. 2 shows 25 a central sectional view. Fig. 3 shows a detached detail of the plunger. Fig. 4 shows a face view of the lock housing. Fig. 5 shows an elevation with portions removed, and Fig. 6 a top view of my whip lock.

The aim of my invention is to provide a 30 whip lock in which the factors of neatness, simplicity of design and durability of construction have been kept in view, the whip socket being so arranged that when the driver desires to leave the vehicle without taking the whip with him he can securely lock the same within the socket.

In carrying out the object of my invention, I provide a whip socket 10, of any conventional form and provided with the usual 40 drain opening 9 within the bottom. At a suitable point this whip socket has a portion removed to form a seat 11 within which is held a lock housing 12. By means of a stop 45 plate 13, the housing is secured at the upper end while at its lower end the housing is supported upon the lateral projection 15, the housing being removably held by means of the screws 14. As shown at 16 the whip 50 socket is provided with a slot through which the upper whip engaging lip 17 extends, this lip forming part of a yieldingly held arm 18 secured within the whip seat 11 by means of the screw 19.

The housing 12 is provided with a longitudinally disposed channel 20 within which

is slidably held the plunger 21, this plunger being provided with a plurality of threaded openings 23 to adjustably receive the operating pin 24 provided with the enlarged head 60 25 by means of which the pin and the connected plunger are operated. Near its upper end this plunger 21 is provided with the seats 26 oppositely positioned as shown in Fig. 3. The plunger 21 is of a length less 65 than the channel 20 and resting upon the upper end of the plunger and against the stop plate 13 is the protractile spring 29 so that this plunger is normally forced into a downward position as disclosed in Fig. 2. 70

As shown in Fig. 5 the housing 12 is recessed and held within this recess 30 are the two inwardly extending spring jaws 32, these jaws being adapted to find engagement within the seats 26 when the plunger is carried in 75 an upward direction.

In referring to Fig. 2 it will be noticed that the major portion or intermediate portion of the yieldingly held arm 18 is obliquely held within the plunger housing and that the operating pin 24 is in engagement with this outwardly extending or obliquely held portion of the arm 18. 80

In referring to Fig. 6 it will be noticed that the whip engaging lip 17 projects into the 85 whip socket, this view disclosing the position of the whip engaging lip 17 when locked. Now when it is desired to lock a whip within the socket the operator simply grasps the protruding head 25 and carries the plunger 90 upward against the tension of the spring 29 so that the spring jaws 32 will engage within the seats 26, as disclosed in Fig. 5. Now as the stem 25 is carried upward it engages the outwardly bent or oblique portion of the 95 yieldingly held arm 18 to force the lip 17 outward to firmly grip and lock the whip stock to securely hold the same within the socket.

As all whip stocks are not of like size if it is found that the lip 17 does not engage the 100 whip stock firmly enough, the operator simply removes the operating pin 24 from within its seating and carries the pin upward into the next seating which will insure the pin being brought up further towards the moving 105 end of the arm 18.

Positioned above the slot 36 within which the operating pin slides is the key hole 35, this key hole being proximal to the upper ends of the spring jaws 32. Now, when it is 110 desired to release the locking mechanism the operator inserts a key 37 the end of which is

stopped against the plunger 21 and then turns the key so that the wings 38 of the key will engage the jaws forcing them outward and permitting the spring 29 to force the plunger downward into normal unlocked position. As the pin 24 descends, the yieldingly held arm 18 flies back into its normal position.

And having thus described my said invention what I claim as new and desire to secure 10 by U. S. Letters Patent is—

A slotted whip socket having in combination, a yieldingly held arm having an obliquely held portion and a whip engaging 15 lip extending through said slot, said arm being secured to said socket, a housing provided

with a plunger channel and a key and pin slot, a perforated and seat-provided spring pressed plunger within said channel, spring jaws within said housing adapted to engage 20 within said plunger seats, an operating stem projecting through said slot and removably held within one of said perforations, said stem riding upon said oblique arm portion, and a key for engagement with said spring 25 jaws all arranged as set forth.

In testimony whereof, I affix my signature, in presence of two witnesses.

WILLIAM H. HEILIGER.
